[57] CLAIM

The ornamental design for an insect trap, as shown and described.

DESCRIPTION

FIG. 1 is a front elevational view of an insect trap showing my new design;

FIG. 2 is a rear elevational view thereof;

FIG. 3 is a left side elevational view, the right side being a mirror image thereof;

FIG. 4 is a cross-sectional view, taken along line 4—4 of FIG. 2;

FIG. 5 is a top plan view thereof; and,

FIG. 6 is a bottom plan view thereof.
